US00D937906S

(12) **United States Design Patent** (10) Patent No.: **US D937,906 S**
(45) Date of Patent: ** Dec. 7, 2021

(54) **PRESSURE VESSEL CLOSURE**

(71) Applicant: **Key Safety Systems, Inc.**, Sterling Heights, MI (US)
(72) Inventors: **Kent Norman, III**, St. Petersburg, FL (US); **William F. McLeod**, Sterling Heights, MI (US)

(**) Term: **15 Years**

(21) Appl. No.: **29/644,672**

(22) Filed: **Apr. 19, 2018**

(51) LOC (13) Cl. **15-02**

(52) U.S. Cl.

USPC **D15/9**; D12/177

(57) **CLAIM**

The ornamental design for a pressure vessel closure, as shown and described.

DESCRIPTION

FIG. 1 is a top perspective view of a pressure vessel closure, showing my new design.

FIG. 2 is a bottom perspective view of my new design shown in FIG. 1.

FIG. 3 is a top view of my new design shown in FIG. 1. FIG. 4 is a bottom view of my new design shown in FIG. 1. FIG. 5 is a side view of my new design shown in FIG. 1. FIG. 6 is a side view of my new design shown in FIG. 1. FIG. 7 is a side view of my new design shown in FIG. 1. FIG. 8 is a side view of my new design shown in FIG. 1; and, FIG. 9 is a cross-sectional view taken from line 9-9 of FIG. 3.

The broken lines depict portions of the pressure vessel closure that form no part of the claimed design.

1 Claim, 3 Drawing Sheets
